[57] CLAIM

The ornamental design for a head rest for a neck cushion, as shown and described.

DESCRIPTION

FIG. 1 is a top plan view of the head rest for a neck cushion showing our new design with the neck cushion being shown in phantom;

FIG. 2 is a front elevational view thereof;

FIG. 3 is a side elevational view thereof, looking from the left side of FIG. 1;

FIG. 4 is a bottom plan view thereof;

FIG. 5 is a rear elevational view thereof; and,

FIG. 6 is a side elevational view thereof, looking from the right side of FIG. 1.

The broken lines are for environmental purposes only and form no part of the claimed design.
